INVENTOR.

BY *Daniel J. Boyer*
George J. Ottsch
ATTORNEY.

UNITED STATES PATENT OFFICE.

DANIEL J. BOYER, OF SOUTH BEND, INDIANA.

ROTATABLE PISTON.

Application filed December 4, 1923. Serial No. 678,495.

To all whom it may concern:

Be it known that I, DANIEL J. BOYER, a citizen of the United States, residing at South Bend, in the county of St. Joseph and 5 State of Indiana, have invented certain new and useful Improvements in Rotatable Pistons, of which the following is a specification.

The invention relates to pistons of internal combustion engines, and has for its object to provide means whereby upon the downward movement of the piston, a slight rotary movement will be imparted to the piston, thereby obtaining equal wear on 10 the cylinder walls and preventing the cylinders from wearing out of round, so that new piston rings or over sized pistons will be effective without the necessity of reborning the cylinders.

20 A further object is to pivotally connect the connecting rods to the pistons, thereby allowing the pistons to rotate, and to provide a spring pressed plunger disposed at an angle to the axis of the pistons, and provided with oppositely disposed pins adapted 25 to be engaged by recesses in the skirts of the pistons, upon downward movement of the pistons. The angular position of the plunger imparts a slight rotation to the pistons.

30 A further object is to pivotally connect the pistons to the connecting rods whereby said pistons may completely rotate and to provide the skirts of the pistons with recesses extending entirely around the same, thereby allowing the pistons to be placed within the cylinders without adjustment in relation to the spring actuated plunger.

With the above and other objects in view 40 the invention resides in the combination and arrangement of parts as hereinafter set forth, shown in the drawing, described and claimed, it being understood that changes in the precise embodiment of the invention 45 may be made within the scope of what is claimed without departing from the spirit of the invention.

In the drawing:—

Figure 1 is a vertical longitudinal sectional view through adjacent cylinders and pistons of an internal combustion engine, showing the piston rotating device applied thereto.

50 Figure 2 is a vertical transverse sectional view through a portion of a cylinder and piston and the piston rotating device.

Figure 3 is a top plan view of the piston rotating device.

Referring to the drawing the numeral 1 designates a conventional form of engine 60 block and 2 cylinders therein. Disposed within the cylinders 2 are pistons 3, which pistons as shown in Figure 1 are on their downward stroke. It has been found that if a slight rotation is imparted to the pistons 3, the wearing of the walls of the cylinders 2 out of round is obviated and consequently new piston rings or over sized pistons will be effective without the necessity of reborning the cylinders. 70

Pivots mounted on headed bolts 4 of the heads of the pistons are U-shaped members 5, between the arms 6 of which the upper ends of the connecting rods 7 are mounted on the pins 8, therefore it will be 75 seen that the pistons 3 may easily rotate during the reciprocation thereof. To prevent the headed bolts 4 from unscrewing, pins 8 are provided, which pins extend through the pistons 3 and into said headed bolts. Se- 80

cured to the under side of the engine block 1 between the cylinders 2 by means of bolts 9 is a plunger casing 10, which casing is provided with a chamber 11, disposed at an angle to the axis of the pistons 3 and preferably in a transverse plane. Slidably mounted within the chamber 11 is a plunger 12, which plunger adjacent its upper end is provided with oppositely disposed lugs 13, which lugs underlie the skirts 14 of the 90 pistons 3, and in positions where they will be engaged by the skirts 14, upon downward movement of the pistons 3 when they are either on the intake or power strokes. Disposed within the chamber 11 of the cas- 95

ing 10 is a coiled spring 15, which spring normally forces the plunger 12 upwardly into engagement with the under side of the engine block 1, which engine block limits its upward movement. Lugs 13 extend 100 upward through slots 16 in the opposite sides of the casing 10, which slots are angularly disposed in relation to the axis of the pistons 3, and guide the pins 13 in their downward movement. 105

Upon the downward movement of the pistons 3, the lugs 13 are engaged by the skirts 14 of the pistons and are received in any of the recesses 17, which extend entirely around the lower edges of the skirts. As the pistons 110 continue their downward movement, the plunger 12 moves at an angle to the axis of

the piston 3 and consequently the lugs 13 will impart a slight rotation to the pistons, thereby insuring a uniform wearing of the walls of the cylinders 2. As the pistons and plunger 12 move downwardly, with the lugs 13 in engagement with the recesses 17, the spring 15 is compressed, consequently the lugs are maintained in the recesses 17 of the pistons during the downward movement of the pistons. Upon upward movement of the pistons the lugs 13 are also maintained in the recesses 17, consequently a reverse slight rotation of the piston is obtained, thereby insuring a uniform circumferential wearing of the pistons and the cylinders 2, which insures a uniform wearing away of the walls thereof and prevents the cylinders from being worn out of round, therefore over sized rings or pistons may be immediately placed in the cylinders without reboring the cylinders.

The invention having been set forth what is claimed as new and useful is:—

1. The combination with a piston disposed within a cylinder, a connecting rod pivotally connected to said piston, of yielding means movable at an angle to the axis of the piston and cooperating with the skirt of the piston whereby during a reciprocation of the piston said piston will be partially rotated.

2. The combination with a piston disposed within a cylinder, a connecting rod pivotally connected to said piston, of means for im-

parting a partial rotation to said piston, said means comprising a member slidably mounted at an angle to the axis of the piston and a lug carried by said slidably mounted member and adapted to engage in a recess in the piston.

3. The combination with a piston disposed within a cylinder, a connecting rod pivotally connected to said piston, of means for imparting a partial rotation to said piston, said means comprising a spring actuated member slidably mounted at an angle to the axis of the piston and a lug carried by said spring actuated member and disposed in a recess in the piston.

4. The combination with adjacent pistons slidably mounted in adjacent cylinders, the lower ends of said pistons being provided with a plurality of recesses, of a spring actuated plunger, said plunger being slidably mounted within a casing disposed at an angle to the axis of the pistons and lugs carried by said plunger and disposed in recesses of the pistons.

5. The combination with adjacent pistons slidably mounted in adjacent cylinders, of means disposed between said pistons and cooperating with said pistons, whereby said pistons will be partially rotated in opposite directions during the reciprocation thereof.

In testimony whereof I affix my signature.

DANIEL J. BOYER.
